METAL CLAD REFRACTORY SHAPES
John L. Cummings, Sr., Horizon House, 31 Island Way,
Clearwater, Fla. 33515
Filed May 20, 1965, Ser. No. 457,294
1 Claim. (Cl. 52—599)

ABSTRACT OF THE DISCLOSURE

This disclosure relates to a method of cladding refractory bricks or other shapes with sheet metal known as metal casings to prevent the brick from falling out during handling and to hold them in place in the walls in which they are used. It is among the objects of this disclosure to provide a metal cased refractory article wherein the casing is interlocked with the refractory material by displacing portions of the metal casing into pre-formed recesses formed by chamfered areas at opposite edges of the refractory bodies. In accordance with the present disclosure, the edges of the refractory material are chamfered to provide a large area of contact for the sheet metal material that is displaced therein as by means of a punch die in a press in which the cladding material is applied to the refractory bodies.

Various means of interlocking metal casing with refractory bodies have been heretofore proposed. One that has been extensively used consists of displacing the metal in a dimple-like recess of the refractory brick or body but this provides an insufficient area of contact and results in the cladding material becoming loose and therefore relatively movable to the refractory body.

A further object of the invention is to provide an interlock of the casing which consists of two parts at the edge of the refractory body over an area where the juxtaposed edges of the cladding sheet material can be displaced into a recess common to both such edges.

The invention will become more apparent from a consideration of the accompanying drawings constituting a part hereof in which like reference numerals designate like parts and in which:

FIGURE 1 is a top plan view of a refractory brick-shaped body with sheet metal cladding applied and interlocked therewith in accordance with the present invention;

FIGURE 2 is an end view of a fragmentary portion of the metal cased refractory article of FIGURE 1 showing the detail of the edge interlock of the casing with a chamfered portion of the refractory body;

FIGURE 3 is a vertical section, partially in elevation, taken along the line 3—3 of FIGURE 1;

FIGURE 4 is a view in perspective of a metal cased refractory body with a hanger strap attached thereto;

FIGURE 5 is a top plan view of the refractory body before cladding;

FIGURE 6 is an end elevational view thereof;

FIGURE 7 a vertical section taken along the line 7—7 of FIGURE 6;

FIGURE 8 an end view of a U or channel-shaped cladding member of which there are two employed in enclosing the brick of FIGURE 1; and,

FIGURE 9 is a side elevational view of the casing shown in FIGURE 8.

With reference to FIGURE 5 of the drawing, the numeral 1 designates a refractory body of what is termed in the industry as a basic refractory capable of withstanding high temperatures for use in open hearth fur-

2

naces and the like, the granular material with a suitable binder being molded in presses and either compacted by vibration or a high pressure to the shape of a brick as is shown in FIGURES 5 through 7. A feature 5 of the invention is molding the brick with chamfered areas designated by the numeral 2 which, as shown in FIGURES 6 and 7, occurs on opposite faces of the brick. FIGURES 8 and 9 show channel-shaped casings 3, which are punched out in a manner to pre-stress the sheet material so that the legs 4 of the channels are biased inwardly, they being shown as spread in FIGURE 8 of the drawing for the purpose of inserting the refractory brick, which is shown in dot and dash lines.

As shown in FIGURE 1, the channel members 3 are 15 provided with legs 4 that are slightly short of half of the width of the brick so as to leave a clearance of space 5, FIGURE 1, so that they cannot abut when assembled, as in FIGURE 1. If the edges designated by the numeral 6 in the drawing did abut, the cladding could not be 20 tightly engaged with the refractory body, as is apparent. When the channel members 3 are assembled, as shown in FIGURE 1, a forming die shaped to conform to the chamfer 2 of the refractory body, displaces the metal in the form of ears 7, FIGURE 2, to conform to 25 and intimately engage the chamfered portions at the edges of the brick. It will be noted that the chamfers 2 and ears 7 provide contact over a relatively wide area to securely interlock the metal casing with the refractory bodies against any displacement. By this construction, the refractory brick 1 can be provided with the 30 chamfered areas 2 in a simple molding operation at opposite edges and the cladding metal can be made to conform to the chamfer because the full pressure on the ear forming dies is available against the resistance of 35 the refractory body 1, thus assuring that the metal casing is tightly and securely engaged with the refractory body 1.

In the construction shown in FIGURE 4, the brick is assembled in the casing material in the same manner 40 as in FIGURE 1, but is provided with a hanger strap 8 having a slot 9 by which it can be mounted to roof or arch suspension supports in a well known manner.

I claim:

A metal clad refractory shape comprising a substantially 45 brick shaped body of a basic refractory material molded to a shape having end faces and side faces and having a chamfered area at opposite edges at substantially the center of the small ends of the brick with the beveled faces of the chamfered area extending at an 50 angle from the end faces of the brick upward toward and to the longitudinal center of the side faces of the brick, U-shaped metal casings enveloping the side faces of said shape having the legs of the casings juxtaposed with space between the edges and having portions of the 55 edges of the legs overlying the chamfered areas, said overlying portions being depressed into intimate contact with the entire surface of the chamfered area of said body underlying said portions to interlock said casing and body.
